B. C. RETTIG

CEILING FAN HANGER

Filed Aug. 27, 1926

UNITED STATES PATENT OFFICE.

BRUCE C. RETTIG, OF FORT WORTH, TEXAS.

CEILING-FAN HANGER.

Application filed August 27, 1926. Serial No 131,928.

My invention relates to ceiling fan hangers and more particularly to fan hangers from which fans may be removed without spilling and wasting the lubricating oils; and the object is to provide a simple construction from which the fans can be removed without tilting the fans to one side and from which the fans may be removed by lifting the fans directly upward and then directly downward for the removal of the fans, and without the necessity of removing the stem from the ceiling. One of the advantages of the improved hanger is that only short ladders are necessary after the first installation. Other objects and advantages will be fully explained in the following description and the invention will be more particularly pointed out in the claims.

Reference is had to the accompanying drawings which form a part of this application.

Fig. 1 is a side elevation of the motor and hanger and stem.

Fig. 2 is a broken vertical section, showing the connection of the stem and lug and motor.

Fig. 3 is a side elevation of the plug or head which connects the stem and the motor.

Fig. 4 is a plan view of the hanger and connecting parts assembled.

Fig. 5 is a plan view of the plug or head.

Similar characters of reference are used to indicate the same parts throughout the several views.

A fan motor 1 is shown in conventional form and a plug or head 2 is provided and slidably mounted in the upper part of the motor casing 3. The head 2 has vertical grooves 4 and the head 2 has seats 5 for lugs 6 which are formed on the upper part of the motor casing 3. The head 2 is provided with cavities 7 and the lugs 6 have tips 8 which seat in the cavities 7. To install the device, place the head above the motor casing and adjust the same that the two lugs 6 will pass down the grooves 4. The head 2 is let low enough so that the head will swing or rotate below the lugs 6 and tips 8. The head 2 is then turned one quarter turn and this

will bring the seats 5 directly under the lugs 6. Then lift the head 2 directly upward. 50 The lugs 6 will fit in the seats 5 and the tips 8 of the lugs 6 will fill the cavities 7. The head 2 may be rigidly secured to the motor casing 3 by set screws 9. Current wires 10 are run down in the hollow stem 11 and out through an opening 12 and run along in a groove 13 in the casing 3 and then they are fastened down on the motor casing by binding screws 14 which connect with the windings of the motor 1. 60

To dismantle the device, loosen the binding screws 14 and take the wires 10 from under the screws 14. Then loosen screws 9 and raise the motor directly upward until the lugs 6 will pass above the head 2. Then 65 turn the motor casing one quarter turn. The lugs 6 and tips 7 can then project in the grooves 4 so that the motor can be let directly downward without tilting and thus be removed from the hanger. 70

What I claim, is,—

1. A fan hanger comprising a motor casing having inwardly projecting lugs on the upper end thereof, a head having vertical grooves in the periphery thereof and seats 75 in the upper surface thereof and cavities in the bottom parts of said seats, tips on the bottom parts of said lugs occupying said cavities, and set screws for securing said head in said casing. 80

2. A fan hanger comprising a motor casing having an upwardly extending cylindrical extension, inwardly projecting lugs formed on said casing, a cylindrical head provided with a hollow rod connection at its 85 upper end and having vertical grooves in the sides thereof for passage of said lugs and having seats in its upper surface for said lugs and cavities in said seats, tips formed on said lugs and adapted to occupy said cavities, and means for securing said head in said casing. 90

In testimony whereof, I set my hand, this 17th day of July, 1926.

BRUCE C. RETTIG.
